UNITED STATES PATENT OFFICE.

ALBERT A. BEST, OF CHICAGO, ILLINOIS.

BUSHING FOR RADIATORS.

Application filed February 7, 1921. Serial No. 443,018.

To all whom it may concern:

Be it known that I, ALBERT A. BEST, a citizen of the United States, residing at Chicago, in the county of Cook and State of Illinois, have invented certain new and useful Improvements in Bushings for Radiators, of which the following is a specification.

This invention relates to bushings for 10 radiators.

The appliance is particularly adapted for use in hot water radiators of the type wherein the hot water is introduced at one end of the radiator and passes out at the opposite 15 end thereof.

One of the objects of the invention is to produce more rapid and equalized heating of radiators.

Another object is to provide an improved 20 bushing or intake coupling for hot water radiators.

Another object is to provide a bushing or coupling which will increase the efficiency 25 of a radiator and protect the same when not in use.

Another object is to provide a bushing or coupling which will direct hot water toward the top of a radiator, will drain the radiator when the same is turned off, and which will 30 serve to keep cold water from flowing from the second loop of the radiator into the first loop thereof.

Another object is to provide a simple, inexpensive, efficient fitting in form of a bushing into which to screw the usual globe valve which controls the admission of hot water 35 into the radiator.

Other, further and more specific objects 40 of the invention will become readily apparent, to persons skilled in the art, from a consideration of the following description, when taken in conjunction with the accompanying drawings, wherein:—

Fig. 1 shows the end view of the bushing.

Fig. 2 is a central longitudinal section of 45 the device and a part of a double pipe radiator within which it is contained.

Hot water radiators come to the user with 50 inlet and outlet openings larger than required for the stem of the valve to be inserted therein and a bushing is required to effectively reduce the opening to accommodate the valve. Furthermore, radiators of this character, have communicating openings 55 between the loops near their upper ends

as well as similar openings near their bottom ends.

The device herein disclosed serves as a bushing for the valve and to forcibly direct the incoming water upwardly through the 60 first loop of the radiator from which point it is distributed laterally through the horizontally extending upper openings and downwardly through the respective loops to the opposite end to the return pipe. 65

The fitting is provided with an angular flange 5, an outwardly threaded part 6 for insertion in the first loop 7 of the radiator and an inner threaded part 8 to receive the valve used to control the flow of water 70 through the radiator.

The device extends inwardly of the loop 7 so that its rear wall 9 is in substantial or partial contact with the short nipple 10 that joins the loops 7 and 11. The wall 9 is 75 curved as at 12 to cause the water to flow upwardly thru loop 7 and thru the opening 13.

The fitting is provided with a very small hole or by-pass 14 in its bottom wall in the 80 same vertical plane with the opening 13 for permitting the water to drain out of the first leg of the radiator to prevent freezing when other parts of the radiator are drained of water. The hole is so small as not to materially interfere with the general circulation of the water as heretofore pointed out. 85 In the event that rear deflecting wall 9 does not tightly fit against the adjacent end of bushing 10, and ordinarily because of irregularities, etc., this is the case, it has been found in practice that the by-pass 14 serves to prevent the flow of cold water from the second to the first loops of the radiator. Thus the intermixture of cold and hot water 90 in the first loop of the radiator is lessened and the efficiency is increased.

The flange 5 bears a mark 15 to indicate the position of the opening 13 when the device is screwed into a radiator. 100

Having described my invention, what I claim as new and desire to secure by Letters Patent, is:

1. A radiator bushing having a single pipe connecting passage therethrough, a deflecting wall for interposition between the first and second loops of the radiator and serving to direct the incoming water upwardly in the first loop, and a by-pass interconnecting the first and second loops. 105 110 115

2. A radiator bushing having a single pipe connecting opening and for insertion into the inlet opening of a radiator, and having a rear deflecting wall for interposition between the first and second loops of a radiator and serving to direct the incoming water upwardly in the first loop, and a by-pass

through the lower portion of the deflecting wall, said by-pass serving as a drain and to prevent cold water flowing from the second loop to the first loop. 10

In testimony whereof I hereunto subscribe my name.

ALBERT A. BEST.
